UNITED STATES PATENT OFFICE

146,278

DESIGN FOR A WALLET

Margaret Christian Dingman, Indiana, Pa.

Application May 8, 1946, Serial No. 129,446

Term of patent 14 years

(Cl. D87—3)

To all whom it may concern:

Be it known that I, Margaret Christian Dingman, a citizen of Canada, residing in Indiana, in the county of Indiana and State of Pennsylvania, have invented a new, original, and ornamental Design for a Wallet, of which the following is a specification, reference being had to the accompanying drawings, forming part thereof.

In the drawings:

Fig. 1 is a bottom view of the wallet showing my new design;

Fig. 2 is a top view;

Fig. 3 is a side view;

Figs. 4 and 5 are end views showing the opposite ends of the wallet;

Fig. 6 is a bottom view of the wallet when it is completely opened; and

Fig. 7 is a top view of the wallet when it is completely opened.

I claim:

The ornamental design for a wallet, substantially as shown.

MARGARET CHRISTIAN DINGMAN.
